ABSTRACT: A spring-wound rotatable cord reel having a fixed magnetized ratchet and a pawl of magnetically attractive material pivotally secured to and rotatable with the reel, the pawl lockingly engaging the ratchet when the reel rotates in a cord-winding direction at a relatively slow rate and orbiting around the ratchet when the reel rotates in a cord-unwinding or payout direction at a faster rate, so that the cord can be rapidly pulled out to the desired length and then gently released to latch or lock it in this position and thereafter, if desired, pulled out again and rapidly released until the entire cord is retracted and wound on the reel.

MAGNETIC RELEASABLE LOCKING MECHANISM FOR CORD REELS

This application is a continuation-in-part of my copending application Ser. No. 738,518 filed June 20, 1968, now U.S. pat. No. 3,528,624, and relates to cord reels equipped with cord winding means, such as a spring, normally urging the cord into its completely retracted position and more particularly with a magnetic ratchet and pawl means for latching the reel in any desired cord payout position and releasing the same to permit the cord winding means to return the cord back to its initial completely retracted position.

Cord-reels, with gravity-actuated-pawl type sheave-latching means as described, for example, in my U.S. Pat. No. 2,314,177 have the disadvantage that they are inoperable when the axis of rotation of the sheave thereof is vertical. Cord-reels with spring-actuated-pawl type sheave-latching means as described, for example, in U.S. Pat. Nos. 2,375,917; 2,391,840 and 2,530,733 have the disadvantage of being more difficult to operate and requiring that the operator hear the clicking sound of the pawl against the ratchet in order to release the cord just at the right moment for its spring wound retraction. Still other conventional latching reels involve mechanisms of undue complexity and multiplicity of parts inherently too expensive, and not as durable or reliable.

The primary object of this invention is to provide a cord reel having means to urge the cord into its wound or stored position which overcomes the disadvantages of the aforementioned conventional reels by employing a fixed magnetic ratchet and a pawl rotatable with the reel and orbiting around the ratchet whereby as the cord is pulled out to the desired length the pawl orbits the ratchet and when the cord is gently released and the reel rotates relatively slowly in a reverse or cord-winding direction, the pawl will lockingly engage the ratchet at a position to retain the cord at the desired extended or payout length; and when the cord is quickly released and the reel rotates rapidly in the cord-winding direction, the pawl again orbits the ratchet until the entire length of the cord is retracted to its original nonextended position.

Another object of the invention is to provide a cord reel of the character described in which the magnetized ratchet is in the form of a notched disc and a means is provided which extends from the periphery thereof adjacent each notch which performs the dual function of leading the pawl into positive locking engagement with the notch when the reel rotates relatively slowly in the cord-winding direction and of engaging the pawl but urging it past the notch when the reel rotates relatively quickly in both the cord unwinding and cord-winding direction, thus simplifying the operation of pulling out the cord to the desired length and releasing it to effect either locking of the cord at said paid out length or allowing it to retract completely to its stored position.

Another object of the invention is to provide a cord reel with means urging the cord to its wound or stored position in which the ratchet is in the form of a permanently magnetized nonrotatable disc with a plurality of spaced notches through its periphery, humps extending radially from the periphery between the notches, an orbiting pawl of magnetically attractable material pivoted to and rotatable with the reel having a protuberance complementary to each notch and stop means causing the protuberance to contact the humps whereby relatively rapid rotation of the reel will create a centrifugal force overcoming the magnetic attraction between the ratchet and pawl so that the latter will orbit the ratchet as its protuberance wipes the humps without engagement in any notch, and whereby upon relatively slow rotation of the reel in the cord-winding direction, the magnetic attraction will overcome the centrifugal force and the humps will act to positively lead the pawl protuberance to drop into a nearby notch.

A further object of the invention is to provide a cord reel of the character described which is relatively easy to manufacture and assemble, inexpensive and easy to operate.

These and other objects of the invention will become more apparent as the following description proceeds in conjunction with the accompanying drawings, wherein:

FIG. 1 is a side elevational view of the cord reel embodying the invention;

FIG. 2 is a sectional view, somewhat enlarged, taken on the line 2-2 of FIG. 1;

FIG. 3 is a sectional view taken on the line 3-3 of FIG. 2 and illustrating the position of the pawl in locking engagement with the magnetic ratchet when the reel rotates relatively slowly in the winding direction;

FIG. 4 is a view similar to FIG. 3 of a modified form of the invention showing the position of the pawl against the magnetic ratchet when the reel rotates relatively slowly; and

FIG. 5 is a view similar to FIG. 4 illustrating the position of the pawl relative to the ratchet when the reel rotates relatively rapidly with centrifugal force urging the pawl away from the ratchet.

The present invention is applicable to both electric and nonelectric cord-reels of the type which generally include a stationary arbor, a cord-storage sheave rotatably mounted thereon and having a hollow cylindrical drumlike hub to or within which the inner end of the cord is anchored and onto which the cord is wound, two generally parallel spaced-apart flanges extending radially outwardly from the hub for laterally confining the cord on the hub, and means urging the cord into the stored or wound position, such as a flat helical cord-winding spring within the hub, having its inner end anchored to the arbor and its outer end anchored to the hub.

The general construction and arrangement of parts of such electric cord-reels are disclosed in U.S. Pat. Nos. 2,375,917; 2,391,840 and 2,948,913 which are herein incorporated by reference. The nonelectric cord-reels omit the electric core within the hub, the electric collector rings and the brushes. Accordingly, since the instant invention is directed to a magnetic releasable locking or latching mechanism for cord reels equipped with a means urging the cord into its stored or wound position, only those parts essential to the invention are shown in the accompanying drawings.

Indicated generally at 11 is a stationary arbor and a stationary bracket or support 12 therefor. While the support 12 is shown as being a generally U-shaped bracket having opposite legs 13 and 14 to which the opposite ends of the arbor 11 are secured, the support can be of any other suitable form or character if desired. The outer reduced ends of the arbor 11 are keyed by any suitable means to the bracket or support 12 by a pair of opposite flats on the arbor and by correspondingly shaped holes in the bracket and there retained by a headed screw 15 threaded into an axial hole in the arbor. The reel includes a sheave which is rotatably mounted on the arbor 11 and includes a hub 16 and a pair of spaced-apart cord-confining flanges 18 extending radially outward from the hub thereof.

The hub 16 of the sheave is preferably formed of two shallow cuplike halves having generally cylindrical outer sidewalls and inner flat radial walls or bottoms with central arbor-receiving holes therethrough, their inner radial walls being arranged back-to-back and secured to each other by any suitable means, one of which cuplike hub portions constitutes the electrical-chamber in which the electric-cord is mounted and the other a spring chamber in which a flat helical cord-winding spring is operatively mounted.

The cord-confining flange 18 on the electrical side of the sheave is preferably formed integrally with a corresponding cuplike hub portion. The flange 18 on the spring side of the sheave is preferably formed separately from the corresponding cuplike hub portion, and extends not only radially outwardly from the cylindrical wall of said hub portion but also extends radially inwardly therefrom and thus encloses the cord-winding spring within such hub portion. The spring within such hub portion (not shown) has an inner end which is anchored in the slot 19 of the arbor and an outer end which is secured to the hub portion. A cord 20 is provided whose inner

end passes through a suitable aperture in the hub and is anchored thereto in the manner disclosed in U.S. Pat. No. 2,948,913, the spring or other means normally acting to retract the cord and wind it around the hub as indicated by the arrow 22 in FIG. 5, the reverse or unwinding direction of the reel for cord extension being shown by the arrow 24 in FIG. 5. The cord 20 may be provided with a conventional electrical plug 26 at its outer end for engagement in a suitable outlet socket.

The present invention comprises a magnetic pawl and ratchet means to permit one readily and easily to pull out the cord and then gently release it to obtain a desired length of payout or to rapidly release the cord for total retraction and winding about the hub back to its initial position.

The pawl is in the form of a generally arcuate finger 28 which is pivoted adjacent one of its ends as at 30 to one of the flanges 18 around an axis substantially parallel to the axis 32 of rotation of the sheave. Adjacent its free end and extending inwardly towards the arbor, the pawl has a protuberance 34 having opposed surfaces 36 and 38.

The pivotal attachment of the pawl to the sheave for rotation therewith is effected, for example, by first mounting the pawl on a tubular stepped rivet 40. Thereafter the rivet 40 is extended through a hole in a boss 42 provided in the flange 18 and there peened. A cap member 44 is then riveted to the outer end of the rivet 42 and a similar diametrically opposed rivet 46.

The cap member 44 has a generally cylindrical flange 48, the edge of which bears against the sheave flange 18. The cap member 44 is also provided with a central inwardly offset annular portion 50, which prevents the axially outward displacement of the magnetic ratchet disc, without however restraining the free rotation of the cap member 44 or the flange 18 mounting the pawl about the stationary arbor 11 as an axis. The flange 18 is also provided centrally thereof with a generally cylindrical inner annular flange 52 which serves to journal the sheave on the uninterrupted cylindrical portion of the arbor 11.

The pawl 28 may be formed of iron or soft annealed steel, such as cold-rolled steel or other equivalent ferrous material which can be magnetically attracted but which can not be permanently magnetized or which does not retain any significant magnetism of its own, independently of the attractive magnetic field otherwise provided by another permanent magnetic source as will appear hereinafter.

The ratchet is generally indicated at 54 and is in the form of a magnetized disc fixedly mounted on or keyed to the arbor in any appropriate manner substantially axially therewith and is adapted to lockingly or releasably engage the pawl which orbits it as the reel rotates. Opening through the periphery 56 of the ratchet disc is a pair of diametrically opposed notches 58 each complementary to the protuberance 35 of the pawl, and therefore each notch includes opposed faces 60 and 62 equivalent to faces 36 and 28 respectively of the pawl protuberance.

In the modified form shown in FIGS. 4 and 5, periphery 56 of the ratchet disc is additionally provided on the side closely adjacent the angulated or locking face end of each notch with an outwardly or radially extending rounded hump 64 whose circumferential length is only a small portion of the distance between the notches.

The ratchet disc is magnetized to provide a field extending radially outwardly from and uniformly its periphery towards the pawl. It may be magnetized, for example, by forming it of a single ply sheet of permanently magnetized hardened steel of Alnico or other material which has been permanently cross-magnetized so that its North pole will extend throughout one face thereof, or at least throughout its peripheral edge, and so that the South pole will extend throughout the other face or at least through its peripheral edge, thereby creating a uniform magnetic attraction of the pawl 28 throughout its peripheral edge.

The ratchet disc is preferably formed of soft or annealed steel, such as cold-rolled steel, and a washer 66 is interposed between the disc and the flange 18, which washer may be formed of a permanently cross-magnetized ferrous material, such as a rubber or rubberlike or other suitable plastic matrix through which permanently magnetizable ferrous particles, such as barium ferrite powder, are uniformly distributed, and which is thereafter permanently cross-magnetized. Such permanently cross-magnetized disc is thus sandwiched between the steel pawl-mounting flange 18 and the steel ratchet disc, thereby forming a magnetic circuit through the flange 18 and the ratchet disc 54. This sandwich arrangement is superior to the one in which the magnetized disc is attached to a nonmagnetic support of flange 18, made of aluminum, plastic or the like; for the pawl is in stronger area of magnetic flux in the sandwich construction, and hence reacts more readily than in the nonsandwich arrangement.

The cap member 44 which encloses the pawl 28 and the notched ratchet disc 54 may be made out of a nonmagnetic material such as aluminum, brass or the like, so as not to divert or dilute the magnetic field of the ratchet disc.

When the cord 20 is pulled out rapidly it causes the reel to rotate at a relatively high speed. The centrifugal force generated causes the pawl to pivot so that its free end containing the protuberance 34 moves away from the ratchet disc 54. At a predetermined velocity of the reel, the centrifugal force generated exceeds the magnetic attraction of the stationary ratchet disc so that the pawl orbits the ratchet disc without engagement of the protuberance in any notch 58, or for that matter with the periphery 56 of the ratchet. The outward movement of the pawl when it orbits in the nonlatching operation is limited by the engagement of the edge of the pawl opposite its protuberance 34 with the annular flange 48 of the cap cover 44, or by the engagement of a rounded bump 68 against said annular flange 48.

When the reel is rotated at a relatively slow speed, the centrifugal force generated is not sufficient to prevent magnetic capture of the pawl by the ratchet disc and hence the protuberance 35 of the pawl will be enabled to lockingly engage in the next oncoming notch. In the unwinding direction shown by arrow 24, the protuberance 68 will not lock or latch in the notch because if the protuberance does happen to fall into a notch the camming engagement of the corresponding faces 60 and 36 of the notch and protuberance respectively will force the protuberance out of the notch. Hence the cord can be pulled out at any speed to the desired length. However, in the winding direction shown by arrow 22, if it is relatively slow, as indicated hereinbefore, the protuberance 34 of the pawl can enter the next oncoming notch and latchingly engage therein, as shown in FIG. 3, because the coating faces 62 and 38 of the notch and pawl protuberance respectively are non-camming.

In use, after the cord is pulled out to the desired length, if it is released gently by frictionally restraining its retraction or rewinding movement, the pawl protuberance will latchingly engage in the next oncoming notch and retain the cord in the desired extended length thereof. When one wishes to effect complete retraction or storage of the cord on the sheave of the reel, he need merely pull out the cord briskly and then release it. The speed or rotation of the reel will be large enough to cause the pawl by the generated centrifugal force to orbit the ratchet disc 54 without having the protuberance 34 enter a notch until the cord is completely retracted.

With respect to the modified device of FIGS. 4 and 5, in the relatively rapid orbiting of the pawl around the ratchet disc the engagement of the rounded hump 68 against the annular flange 48 of the cover so confines the pawl that its protuberance 34 always wipes the high points 64 on the disc. Thus, when the reel rotates relatively rapidly, the wiping action of the humps 64 against the protuberance of the pawl apparently aids the generated centrifugal force in keeping the pawl protuberance from dropping into the ratchet notch. When the cord is pulled out, the pawl generally orbits slowly around the fixed

ratchet, and the humps or high points 64 tend to magnetically recapture and retain the pawl more firmly; and thus when the reel rotates relatively slowly upon release of the cord in its cord-winding direction, the same humps tend to lead the pawl protuberance into the next oncoming notch.

It should be understood that while the humps 64 on the periphery of the ratchet disc are shown as discrete enlargements extending radially outwardly of the periphery, they may be formed of a gradual increase of the radius of the disc from a particular locus on the periphery up to a point adjacent the corner 70 of the rounded camming face 60 of the notch. Also, although the ratchet disc is shown as containing two notches 58, one notch can also be employed as well as three or more equally spaced around the periphery, as also can more than one pawl if desired.

While a preferred embodiment has here been shown and described, it will be understood that a skilled artisan may make variations without departing from the spirit of the invention.

The invention I claim is:

1. In a rotary cord reel including means urging the cord into a wound position, a fixed magnetized ratchet and a pawl of magnetically attractable material pivoted to said reel and rotatable therewith so that said pawl orbits said ratchet and lockingly engages said ratchet when said reel rotates at a relatively slow speed in a cord-winding direction and said pawl does not lockingly engage said ratchet when said reel rotates at a greater speed in either direction.

2. In a rotary cord reel including means urging the cord into a wound position, a fixed magnetized ratchet and a pawl of magnetically attractable material pivoted to said reel and rotatable therewith so that said pawl orbits said ratchet and lockingly engages said ratchet when said reel rotates at a relatively slow speed in a cord-winding direction and said pawl does not lockingly engage said ratchet when said reel rotates at a greater speed in either direction and a fixed arbor about which said reel rotates, said ratchet including a disc keyed to said arbor, a magnetizable metal plate carried by said reel and a washer interposed between said disc and plate comprised of permanently cross-magnetized particles in a plastic matrix.

3. The combination of claim 2 in which said ratchet disc includes at least one notch opening through its peripheral edge and said pawl includes a protuberance complementary thereto and engageable therein.

4. The combination of claim 3 and means protruding from said ratchet engageable with said pawl to aid in keeping said pawl protuberance out of said notch when reel rotates relatively rapidly and to lead said pawl protuberance into said notch when said reel rotates relatively slowly in the cord-winding direction.

5. The combination of claim 3 wherein said notch includes a camming face adapted to expel a pawl when the reel rotates in one direction and a locking face adapted to retain a pawl when the reel rotates in an opposite direction.

6. In a rotary cord reel including means urging the cord into the wound position, a fixedly mounted ratchet disc including at least one notch in its peripheral edge, a pivotally mounted orbiting pawl rotating with said reel and including a protuberance complementary to said notch, means creating a magnetic field drawing said pawl towards said ratchet disc and means protruding from said peripheral edge of said ratchet disc, said magnetic field being of strength sufficient to hold said pawl protuberance against said peripheral edge of said disc when said reel rotates relatively slowly in the winding direction to allow said pawl protuberance to engage said notch, the magnetic field strength being insufficient to overcome the centrifugal force urging said pawl away from said disc when said reel rotates more rapidly in either direction, said means protruding from said peripheral edge engaging said pawl protuberance performing the dual function of assisting in keeping said pawl protuberance out of engagement with said notch when said reel rotates relatively rapidly and positively leading said pawl protuberance into said notch when said reel rotates relatively slowly in the winding direction.

7. The combination of claim 5 wherein said notch includes a camming face coacting with a similar face on said pawl protuberance to urge said pawl protuberance out of said notch when a pull is exerted on the cord and a locking face in said notch coacting with a similar face on said pawl protuberance to lock said pawl protuberance in said notch when the cord is released.

8. In a rotary cord reel including means urging the cord into the wound position, a fixedly mounted ratchet disc including at least one notch in its peripheral edge, a pivotally mounted orbiting pawl rotating with said reel and including a protuberance complementary to said notch, means creating a magnetic field drawing said pawl towards said ratchet disc and means protruding from said peripheral edge of said ratchet disc, said magnetic field being of strength sufficient to hold said pawl protuberance against said peripheral edge of said disc when said reel rotates relatively slowly in the winding direction to allow said pawl protuberance to engage said notch, the magnetic field strength being insufficient to overcome the centrifugal force urging said pawl away from said disc when said reel rotates more rapidly in either direction, said means protruding from said peripheral edge engaging said pawl protuberance performing the dual function of assisting in keeping said pawl protuberance out of engagement with said notch when said reel rotates relatively rapidly and positively leading said pawl protuberance into said notch when said reel rotates relatively slowly in the winding direction wherein said ratchet disc includes a pair of diametrically spaced notches and said means protruding from said peripheral edge of said disc is a hump leading to said face opposite said locking face of said notch.

9. The combination of claim 5 and means limiting outward movement of said pawl as it orbits said ratchet disc so that said pawl protuberance engages said means protruding from said peripheral edge of said disc.

10. In a spring-powered rotary cord-reel including a cord-winding sheave having a hub and a pair of spaced cord-confining flanges extending radially therefrom with a cord having an inner end secured to said hub and adapted to be spring-wound thereon; a magnetic reel locking and release mechanism comprising a ratchet disc nonrotatably mounted adjacent said sheave and generally coaxial therewith, at least one notch opening through the peripheral edge of said ratchet disc, an orbiting pawl pivoted to said sheave and including a protuberance complementary to said notch, means creating a magnetic field acting to draw said pawl towards said ratchet disc of such magnitude that when said sheave is caused to rotate relatively rapidly the centrifugal force generated is greater than the magnetic field strength so that said pawl is urged outwardly of said disc and when said sheave is caused to rotate relatively slowly, said magnetic field strength will capture said pawl and allow its protuberance to enter said notch and be lockingly retained therein, and means limiting the pivotal movement of said pawl outwardly away from said ratchet disc so that said protuberance of said pawl will contact the periphery of the ratchet disc during relatively slow orbiting of said pawl around said ratchet.

11. In a spring-powered rotary cord-reel including a cord-winding sheave having a hub and a pair of spaced cord-confining flanges extending radially therefrom with a cord having an inner end secured to said hub and adapted to be spring-wound thereon; a magnetic reel locking and release mechanism comprising a ratchet disc nonrotatably mounted adjacent said sheave and generally coaxial therewith, at least one notch opening through the peripheral edge of said ratchet disc, an orbiting pawl pivoted to said sheave and including a protuberance complementary to said notch, means creating a magnetic field acting to draw said pawl towards said ratchet disc of such magnitude that when said sheave is caused to rotate relatively rapidly the centrifugal force generated is greater than the magnetic field strength so that said pawl is urged outwardly of said disc and when said sheave is caused to rotate relatively slowly, said magnetic field strength will capture said pawl and allow its protuberance to enter said notch and be

lockingly retained therein, and means limiting the pivotal movement of said pawl outwardly away from said ratchet disc so that said protuberance of said pawl will contact the periphery of the ratchet disc during relatively slow orbiting of said pawl around said ratchet wherein said pawl limiting means includes a cover for said ratchet disc and pawl including an annular wall, a portion of the edge of said pawl opposite its protuberance being adapted to engage said annular wall when said pawl orbits said ratchet relatively rapidly.

12. The combination of claim 11 wherein said notch includes opposed circumferentially spaced faces, one of which is adapted to cammingly engage a corresponding face of said pawl protuberance to permit release of said protuberance from said notch when a pull is exerted on the cord to unwind it

from the sheave, the other face of which coacts with a corresponding face of said pawl protuberance to lock said protuberance in said notch when the cord is released and the sheave rotates relatively slowly in a winding direction.

5 13. The combination of claim 12 wherein said ratchet disc includes a pair of diametrically opposed notches.

10 14. The combination of claim 10 wherein said ratchet disc and one of said cord-confining flanges is made of a magnetizable metal and said means creating the magnetic field includes a washer comprised of permanently cross-magnetized particles distributed in a plastic matrix and interposed between said ratchet disc and said one cord-confining flange.
